UNITED STATES PATENT OFFICE

146,518

DESIGN FOR A HANDLE FOR COOKING VESSELS AND THE LIKE

Alfred Faustin Ramsthal, West Bend, Wis., assignor to West Bend Aluminum Company, West Bend, Wis., a corporation of Wisconsin

Application January 31, 1946, Serial No. 126,124

Term of patent 14 years

(Cl. D44—29)

To all whom it may concern:

Be it known that I, Alfred Faustin Ramsthal, a citizen of the United States, residing at West Bend, in the county of Washington and State of Wisconsin, have invented a new, original, and ornamental Design for a Handle for Cooking Vessels and the like, of which the following is a specification, reference being had to the accompanying drawing, forming a part thereof, and in which:

Figure 1 is a side elevation and Figure 2 is a top plan view of a cooking vessel handle showing my new design;

Figure 3 is an end elevation viewing the inner end of the handle; and

Figure 4 is an end elevation viewing the outer end of the handle.

I claim:

The ornamental design for a handle for cooking vessels and the like, as shown.

ALFRED FAUSTIN RAMSTHAL.
